UNITED STATES PATENT OFFICE

EUGÈNE MARIUS VEYRON, OF LYON, FRANCE, ASSIGNOR TO PAPETERIES NAVARRE, OF LYON, FRANCE, A CORPORATION OF FRANCE

PAPER-MANUFACTURING MACHINE WITH RAISING FELT

Application filed October 26, 1929, Serial No. 402,728, and in France October 31, 1928.

This invention has for its object improvements to machines for the manufacture of paper in which the raising is performed automatically by means of a raising felt.

5 The objects of the said improvements are:—
 1. To provide for the automatic raising of the sheet whatever the cleanliness and permeability of the raising felt may be;
 2. To absolutely avoid the production of mashings on the sheet being raised on account of the possibility of considerably reducing the contact pressure between the felt and the cloth roller without impairing the reliability of the raising of the sheet;

10 3. To provide for a longer life of the raising felt by equal output, as a result of the voids in the felt being kept open by the suction effect;

4. To increase the dehydration capacity of the wet part without increasing the strain on the cloth;

20 5. To provide for an increased linear speed without danger of wrinkling or tearing off the sheet when being raised;

25 6. To improve the quality as a result of the dehydration of the pulp on both sides of the sheet.

Generally stated, the invention is characterized in that the raising press of the ordinary machines is replaced by a suction cylinder mounted upon a rocking lever device allowing an accurate adjustment of the desired contact pressure between the felt and the cloth, the rocking levers being fitted with an oil damper comprising a system for compensating any oil loss.

Another characteristic resides in the provision of trimming pick-up cylinders provided with a setting and disengaging device the details of which are to be dealt with hereinafter.

Figure 1 is a general view showing the arrangement of the suction cylinder.

45 Figure 2 is a top plan view corresponding to Figure 1.

Figure 3 is a cross sectional view showing the construction of one rocking lever.

50 Figure 4 is a cross sectional view taken on line 4—4 of Figure 3.

Figure 5 is a cross sectional view taken on line 5—5 of Figure 3.

Figure 6 is a cross sectional view taken on line 6—6 of Figure 3.

Figure 7 is a top plan view corresponding to Figure 3. 55

Figure 8 is a cross sectional view taken on line 8—8 of Figure 9 and showing the oil damper device.

Figure 9 is a cross sectional view taken on line 9—9 of Figure 8. 60

Figure 10 is a cross sectional view taken on line 10—10 of Figure 8 and showing a tightening partition.

Figure 11 is a detail view of the oil make-up valve. 65

Figure 12 is a cross sectional view taken on line 12—12 of Figure 8.

Figure 13 is a further sectional view taken on line 13—13 of Figure 8. 70

Figures 14 and 15 are detail views.

Figure 16 is a cross sectional view of a trimming pick-up cylinder and its frame.

Figure 17 is a side view corresponding to Figure 16. 75

Figures 18 to 21 relate to the disengaging device for the trimming pick-up cylinders.

In order to permit the mounting of suction cylinder 1 upon adjustable rocking levers, it is provided at both ends thereof with a supporting arm 2 to which the related bearing of the said cylinder is secured. The arm comprises two hinges, viz., hinge 3 on upright 4 and hinge 5 between the said arm and the lever 6 of the scale. A stay 7 hingedly secured at 8 and resting on a boss 9 serving as a guide for the same, maintains the cylinder 1 in raised position when the cloth and felt are to be renewed. For this purpose the arm 2 is loosened from the end 5 of the scale simply by manual pulling out of the grip pin 10. 80

The suction cylinder 1 has its inner suction chest connected as usual through hoses 11 to the vacuum station 12 by means of the transverse general manifold 13. 85

Each rocking lever device comprises a lever 6 hingedly secured at 5 to the rocking supporting arm as described above, the point 14 bearing upon a knife-edge 15. The said lever 100

6 is hingedly secured at 16 to a twin rod 17 by which it is connected to the damper 18.

A counterpoise 19 adapted to be shifted by means of a screw or otherwise allows the pressure between the suction cylinder 1 and the cloth roller 20 to be adjusted.

A stop 21 secured upon the rocking lever carrying upright 22 and fitted in the recess 23 in the lever, prevents the swinging of the 10 knife-edge 15 and provides for the accurate co-incidence of the hinge holes at 5, so that the pin 10 may be driven in and out easily.

The damper or moderator 18 is of the oscillating piston type. The oscillating piston 25 15 is provided with a pair of valves 24 for the purpose of allowing the filling of the chambers 26 formed by the piston walls on either side of the joint block 27. The filling of both chambers is thus effected simply by 20 swinging the piston by hand. Moreover, these valves provide for the automatic make-up of any oil loss by drawing from the oil supply 28 arranged at the top portion of the damper casing, the small working displacements of the piston being sufficient for the 25 purpose.

The object of the damper is to wholly eliminate the vibrations and oscillations of the suction cylinder which would infallibly result in 30 the production of mashed or wrinkled sheets by reason of variations in the contact pressure.

The trimming pick-up cylinders are shown at 29 in Figures 16 and 17. They consist of 35 a cylinder lined with flexible india rubber and a frame 30 carrying the hinged trimming scrape-off blade 31. The cylinder is mounted in ball bearings arranged in the frame which is adapted to be shifted along a cross bar 31 40 parallel to the suction cylinder and hingedly mounted in the pair of supporting arms and projecting through two hubs thereon.

This arrangement allows the adjustment of 45 the pick-up cylinders according to the size and also permits the disengagement of the cylinders as desired. The disengaging device comprises a stop 33 secured to the cross-bar carrying the pick-up cylinders and actuated from the operator's side by means of a cam 50 provided with an operating handle.

It is to be understood that the embodiment just described is by no ways of limitative character and lends itself to all desirable modifications without thereby departing 55 from the scope of the invention as set forth in the appended claims.

Claims:

1. In machines for the manufacture of paper where the raising is performed automatically by means of a raising felt, the improvement consisting in the provision of a suction cylinder operating as a sheet raising device, the said suction cylinder being mounted upon adjustable rocking arms the 60 oscillations of which are damped in order to 65

avoid the mashing or wrinkling of the sheet.

2. In machines for the manufacture of paper according to claim 1, the provision of an adjustable trimming pick-up cylinder device combined with a disengaging device allowing the said pick-up cylinders to be made 70 inoperative when necessary.

In testimony whereof, I affix my signature.

EUGÈNE MARIUS VEYRON.
